UNITED STATES PATENT OFFICE.

ROBERT E. WARD, OF KANSAS CITY, MISSOURI.

HOSE-SUPPORTER.

1,167,669.

Specification of Letters Patent. Patented Jan. 11, 1916.

Application filed February 25, 1915. Serial No. 10,479.

To all whom it may concern:

Be it known that I, ROBERT E. WARD, a citizen of the United States, residing at Kansas City, in the county of Jackson and 5 State of Missouri, have invented certain new and useful Improvements in Hose-Supporters; and I do declare the following to be a full, clear, and exact description of the invention, such as will enable others skilled in 10 the art to which it appertains to make and use the same.

This invention relates to improvements in hose supporters and more particularly to that type which are adapted to be fastened 15 around the leg and worn below the knee such as are usually employed by men.

The object of the invention is to provide a hose supporter of this character which is so constructed that it will readily conform 20 to the shape of the leg of the wearer and which has an elastic portion so positioned that it will be disposed on the flat inner face of the leg when the device is applied, so that the tension on said elastic portion will be the 25 same throughout its width and thus prolong the life of said elastic portion.

Another object of the invention is to so construct and connect the elastic portion of the garter or hose supporter that it can be 30 quickly removed and a new portion substituted when worn or otherwise injured, and which is quickly adjustable to adapt the supporters to fit legs of different sizes.

With these and other objects in view, the 35 invention consists of certain novel features of construction, and the combination and arrangement of parts as will be more fully described and claimed.

In the accompanying drawings: Figure 1 40 represents a perspective view of this improved garter applied. Fig. 2 is a horizontal section thereof.

With the elastic garters of the type above set forth, the elastic leg encircling band is 45 subjected to an uneven tension at the lower part or edge as the band encircles the leg at the greatest circumference and therefore the lower threads are the first to break and as these continue to break from the bottom to 50 the top, the garter slips down and sooner or later becomes useless as a supporter.

In the embodiment illustrated, this improved supporter comprises a substantially 55 triangular tab or pad 1 which is preferably made of soft leather and in the drawings is shown as provided with a pocket 2 equipped

with a suitable closure 3 here shown in the form of a flap adapted to be detachably connected to the body of the pad by a suitable snap fastener 4, or other suitable fastening element. A stocking engaging member 5 is here shown connected with the depending point 6 of the pad 1 and may be of any suitable or desired construction. The other points 7 and 8 or corners of the pad 1 are 60 shown oppositely disposed and a soft leather strap 9 is secured to one of said points being here shown stitched thereto. The strap 9 is of a length designed to encircle about three-fourths of the circumference of the leg of 70 the wearer and detachably secured to the free end thereof is an elastic loop 10, said loop being here shown composed of a strip of elastic webbing folded transversely midway its ends and with its free ends inserted 75 between the jaws of a clamping member 11 mounted on the free end of the leather strip 9. A hook 12 is shown mounted on the loop 10 being here shown mounted on a slotted plate 13 through the slot of which the elastic 80 webbing constituting the loop is passed, as shown clearly in Fig. 2. Secured to the point or corner 8 of the pad 1 is an eye 14 designed to receive the hook 12 whereby the loop 10 is detachably connected with said 85 pad 1.

When it is desired to adjust the loop 10 to adapt the supporter to fit legs of different sizes, all that is necessary is to open the jaws of the clamp 11 and position the ends 90 of the strip forming said loop to lengthen or shorten the loop according to the wishes of the user, and should for any reason this loop become worn or injured, it may be readily removed and a new one substituted simply by opening the jaws of the clamp 11, removing the ends of the strip constituting the loop, slipping off the slotted plate 13 which carries the hook 12, then inserting 95 said plate on another piece of elastic webbing, and inserting the ends thereof in the jaws of the clamp 11 and closing said clamp, and the device will be ready for use.

As shown in Fig. 1 when this improved 100 supporter is in use, the pad 1 will be positioned on the outer side of the leg with the elastic loop disposed on the inner flat side of the leg so that the tension on said loop will be equal through its width and thus prevent undue strain on either of the edges of 110 said loop, such as would cause it to quickly wear out in the manner above described.

The strip 9 being composed of soft leather would readily conform to the shape of the leg of the user.

The pads 1 of both of the garters may be 5 equipped with pockets as above described, or one, only of each pair may have such a pocket and said pocket may be used for many purposes, for carrying money or valuables at the will of the user.

10. From the above description, it will be obvious that while this device is very simple and cheap to manufacture, it will be very efficient in operation and the construction thereof is designed to prolong the life of the 15 supporter beyond that which is constructed wholly of elastic webbing.

I claim as my invention:

1. A hose supporter comprising a pad, a stocking engaging member carried thereby, 20 an inelastic strip secured at one end to said pad and an elastic strip adjustably connected with the free end of said inelastic strip, and means for detachably connecting said elastic strip with said pad.

25. 2. A hose supporter comprising a pad, a stocking engaging member carried thereby, a soft leather strip secured at one end to said pad and of a length to extend around the greater portion of the circumference of 30 the leg of the wearer, an elastic loop de-

tachably connected with the free end of said strip, and means for detachably connecting said loop and pad.

3. A hose supporter comprising a substantially triangular member, a leg encircling member connected at one end to one corner of said pad, said member being composed of detachably connected elastic and inelastic strips, and means for detachably connecting the other end of said member to the 40 inner corner of said pad, and hose engaging means carried by said pad.

4. A hose supporter comprising a pad, a stocking engaging member carried thereby, a soft leather strip secured at one end to 45 said pad, a clamp secured to the free end of said strip, an elastic strip folded transversely to form a loop with the free ends thereof inserted in said clamp, a slotted plate slidably mounted on said loop and having a fastening element thereon, and a co-operating fastening element on said pad.

In testimony whereof I have hereunto set my hand in presence of two subscribing witnesses.

ROBERT E. WARD.
